UNITED STATES PATENT OFFICE

LOUIS GRAVEURE, OF NEW YORK, N. Y.

LOCK

Application filed October 8, 1927. Serial No. 224,784.

This invention relates to a lock intended for use upon chests, drawers, doors or any other article wherein a locking device is required. The object of the invention is to provide a lock of simple, yet sturdy construction, which may be made in many pleasing ornamental forms; which is so constructed that the same may be attached by anyone without any particular skill in carpentry and which, when attached cannot be removed so readily or broken surreptitiously.

With these objects and such other objects as may hereinafter appear, in view, I have devised the particular arrangement of parts described below and particularly pointed out in the claim appended hereto.

Reference is to be had to the accompanying drawing, forming a part hereof, in which

Figure 1 is a front elevation of my improved lock;

Figure 2 is a sectional view on the line 2—2 of Figure 1, looking in the direction of the arrows, the lock mechanism and bolt not being shown in section in order to more readily disclose the construction of the important elements of the device;

Figure 3 is a front elevation of the lock with the casing or cover member swung away from the attaching plate and keeper; and

Figure 4 is a sectional view on the line 4—4 of Figure 1, looking in the direction of the arrows.

Throughout the various views of the drawings, similar reference characters designate similar parts.

In the embodiment of my invention disclosed in the accompanying drawing, 1 indicates a portion of a drawer or other movable part of an article of furniture to which my improved lock is adapted to be attached and 2 indicates a fixed part of said article of furniture located adjacent to the drawer or movable part 1. The fixed part 2 is usually a partition or the like extending across the article 45 of furniture directly above the drawer. If

the lock is applied to a door or other hinged or swinging part, the same would be indicated at 1 and the door frame at 2. Assuming therefore that the lock is to be applied to a drawer 1, 3 indicates a flat metal attaching plate, which is secured against the outer face of the drawer 1 by means of a plurality of screws 4 or other similar fastening members. The plate 3 may be of any suitable form, this being dependent upon the general shape in which the lock is to be made and said plate 3 is provided with an extended or depending lower end 5 which terminates in a hinge 6. Said hinge 6 engages with the sloped lower end 7 of a cover member or casing 8. This cover member or casing 8 is so shaped that it completely covers the plate 3 and encloses the same by means of its integrally formed peripheral flange 9. The upper end of the casing 8 is extended well above the upper edge of the plate 3 as shown at 10 and said extended part 10 of the casing 8 is adapted to fit over and enclose a keeper attachment plate 11. Said keeper attachment plate 11 is secured to the fixed part 2 of the article of furniture by means of securing screws 12 or other similar fastening means.

It will be seen from the foregoing that when the lock is in its closed position, as is disclosed in Figures 1 and 2, the casing 8 completely encloses all operating parts and provides an extremely smooth and finished appearance to the lock. It also provides a substantially large area, which may be ornamented in various ways to match the article of furniture to which the lock is adapted to be attached.

The lock mechanism is shown at 13, the same being contained within the conventional metal casing or container and this is secured to the inner face of the casing 8 in any suitable way as by attaching screws 14. These screws 14 are preferably so attached that they thread into the inner side of the

casing 8 and are neither visible nor accessible from the outer side of the casing.

The casing 8 is provided with a keyhole 15 which registers with a similar keyhole in the lock mechanism case in the conventional way.

At 16 is shown a bolt, which is projected out of the mechanism 13 or withdrawn in the conventional way by means of a key inserted in the keyhole 15. Said bolt 16 is adapted to slide through a U-shaped keeper 17 secured to or integrally formed on the plate 11. A similar U-shaped retaining member 18 is formed at the upper end of the plate 3 and the same is adapted to register with the part 17 so that the bolt 16 may be projected through both of the parts 17 and 18 to retain the lock in closed position as is shown in Figure 2. The lock mechanism is so arranged that when the bolt 16 is withdrawn from the keeper member 17 and the lock is thus in its open position, said bolt member can only, by manipulation of the key, be withdrawn a short distance and will retain its position within the member 18 as is indicated in dotted lines in Figure 2. The lock mechanism for performing this function is not disclosed in detail since mechanisms of this type are quite common and any one of the well known kind may be used. The retention of the bolt 16 within the member 18 holds the casing 8 and the plate 3 in their completely connected position. When it is desired to secure access to the lock mechanism 13, the finger or a suitable tool may be inserted from the rear of the casing 8 and the bolt member 16 may be pressed down so that it is completely withdrawn out of the member 18. Thereupon the casing 8 may be swung downwardly on its hinge 6 as disclosed in Figure 3 so that the lock mechanism is accessible and the attaching plate 3 is uncovered.

It will be seen from the foregoing, that when the lock is in its closed position, all fastening means, such as the attaching screws 4 and 12, and the lock mechanism screws 14 are completely covered by the casing 8. Thus, the unauthorized tampering with the lock is prevented. The lock is also so constructed that no parts of the article of furniture to which it is to be attached need be in any way cut or mutilated for the purpose of securing the lock in position. The casing 8 is also so formed that the complete lock is of the external type and said casing may be highly ornamented and so formed that the lock, instead of detracting from the appearance of the article of furniture, will greatly aid its appearance.

Having described one embodiment of my invention, it is obvious that the same is not to be restricted thereto, but is broad enough to cover all structures coming within the scope of the annexed claim.

I claim:

A lock having a securing plate, a keeper, a casing pivotally attached to said plate and enclosing the keeper, a bolt for engagement with the keeper, and means on the securing plate constantly engaged by the bolt to hold the casing in a position to cover its securing plate when the lock is either in its closed or open position.

Signed at the city, county and State of New York, this 7th day of October, 1927.

LOUIS GRAVEURE.
